UNITED STATES PATENT OFFICE.

EMANUEL HAUSE AND FRANKLIN B. GRANGER, OF SOMERSET, PA.

ROTARY ENGINE.

SPECIFICATION forming part of Letters Patent No. 239,953, dated April 12, 1881.

Application filed August 30, 1879.

To all whom it may concern:

Be it known that we, EMANUEL HAUSE and FRANKLIN B. GRANGER, of Somerset, in the county of Somerset and State of Pennsylvania, have invented certain new and useful Improvements in Rotary Engines; and we do hereby declare that the following is a full, clear, and exact description of the invention, which will enable others skilled in the art to which it applies to make and use the same, reference being had to the accompanying drawings, which form a part of this specification.

Figure 1 is a perspective view. Fig. 2 is a side view, the covering-plate of the engine having been removed. Fig. 3 is a longitudinal sectional view of the engine.

Corresponding parts in the several figures are denoted by like letters of reference.

This invention relates to rotary engines; and it consists in certain improvements in the construction of the same, which will be hereinafter fully described, and particularly pointed out in the claim.

In the drawings hereto annexed, A and B represent the furnace and boiler, which form the body of our improved engine, and which are supported upon the wheels C C' D D by spindles E E and by the front axle, F, which latter is pivoted under the front end of the boiler.

Upon the furnace A is secured the casing G of the engine. Said casing, which is approximately cylindrical in shape, carries on top the valve-chamber H.

Within the casing G is formed a recess, I, slightly oval in shape, eccentrically in which (or, more properly, in the sides of the casing adjoining) are bearings for the main shaft J of the engine. Said shaft, which projects beyond the casing on both sides, is provided with an additional box or bearing, K, consisting of a bracket projecting upwardly from the top of the furnace.

Upon shaft J, within recess I, is formed or secured a bulge or disk, L, fitting between the sides of the casing and against the top of the recess. Transversely in said disk, and longitudinally with the shaft J, is formed a slot, M, to accommodate the sliding plate N. The main shaft, it will be observed, has its bearings at such a point in the elliptical case that the slid-

ing plate shall fit within the sides of the latter at any position occupied by the rotating shaft.

Projecting upwardly from the recess I is a small transverse recess, Q, in which is fitted 55 a packing-strip, R, forced by coiled springs down against the disk L.

In the upper part of casing G, above the recess I, and centrally under the valve-chamber, with which it communicates through a channel, T, is formed the exhaust-chamber U.

V W are the steam-entrances, which are located respectively in front and rear of the channel T, and which are connected by channels X X with the recess I on opposite sides 65 of the main shaft. A valve, Y, sliding longitudinally in the valve-chamber is of sufficient size to cover at the same time the opening T and either one of the steam-entrances, a recess, Z, in the under side of said valve serving to form a connection between the opening T and the steam-entrance, covered at the time by the valve.

The valve-chamber H is provided with a horizontal partition, A', having a single central opening or steam-entrance, B', serving to connect the upper compartment, D', with the lower, E'. A valve, F', sliding longitudinally in the compartment D' of the valve-chamber, may be adjusted, in the manner hereinafter to 70 be described, over the said opening B', thereby cutting off the steam.

In a bracket, G', projecting rearwardly from the rear side of the casing G, is formed a bearing for a crank-lever, H', the upper extremity 75 of which is pivoted to the outer end of the operating-rod I' of valve Y, which extends out through a suitable opening in the rear end of the valve-chamber. The lower end of lever H' forms a handle, within convenient reach of 80 the attendant, whose station is behind the body of the machine. It will be observed that by shifting the position of the lever the valve Y may be adjusted over either one of the openings V W, which is thus connected with the 85 exhaust-chamber.

The operating-rod F'' of the valve F' extends through an opening in the forward end of the valve-chamber, and its outer extremity is pivoted to a vertical lever, I'', secured to a 90 transverse horizontal shaft, J', having its bearings in a bracket, K', upon the front side

of casing G. The end of shaft J' is provided with a downwardly-projecting crank or lever, L', having a curved or segmental slot, M', in which is fitted a slide, N'. Pivoted to one end 5 of said slide is a link, O', connecting it with the forward end of a lever, P', pivoted to the side of the casing, the rear end of which lever is confined within a guide-slot, Q', and within reach of the attendant. To the other 10 end of the slide N' is pivoted the forward end of a bracket, R', forming part of a sectional ring or band, S', adjusted around a grooved eccentric-disk, T', secured upon the outer end of the main shaft J.

15 When the machine is in operation the valve F' is continually reciprocated by the mechanism described, the length of stroke being regulated by raising or lowering lever P'. This is in order to cause the machine to be operated 20 to a greater or less extent by the expansion of steam, by which considerable saving is effected.

Upon the opposite end of the main shaft is keyed a sliding clutch-collar, U', operated by a forked lever, V', pivoted in a suitably-arranged bracket, W', within reach of the attendant. The clutch-collar U' is adapted to engage a clutch, X', upon a pinion, Y', which is loose upon the shaft. Pinion Y' engages, either direct or through an intermediate cog-wheel, Z', a gear-wheel, A², upon the drive-wheel C, to which motion is in this manner transmitted.

The operation of the engine is as follows: A pipe, B², conducts the steam from the boiler 35 to the upper compartment of valve-chamber H, from which, supposing the opening B' to be unobstructed, it passes into the lower compartment, E'. Now, supposing the openings T W to be covered (and connected) by the valve 40 Y, the steam will pass through the opening V and channel X connected with said opening, into one side of the cylinder, where it strikes one side of the sliding plate N, it being excluded from the other side by the arrangement of packing-strips, above described. The 45 pressure upon plate N rotates the shaft until the ends of the plate reach the respective openings of channels X X, which, of course, should be so arranged as to be passed at the same time by the ends of the plate. As soon 50 as the said openings are passed the steam confined in the chamber bounded by plate N and the cylinder-walls escapes through channel X in the rear of the case-opening W, under 55 valve Y, through channel T, and into the ex-

haust-chamber, from which it escapes through a suitably-arranged pipe, C², or is conducted to a condenser. At the same time steam is admitted from opening V to the opposite side of plate N, thereby continuing the operation 60 of the engine.

To reverse the engine it is only necessary to change the position of valve Y so as to cover and connect the openings T V and admit the steam through opening W. To stop 65 the engine the valve F' is operated by the mechanism above described in such manner as to place it over the opening B', thus cutting off the steam.

In the sides of the casing G, around the 70 main shaft and surrounding the operating-rods of the valves Y F', we adjust suitable packing-boxes D², by which steam-tight joints are formed.

From the foregoing description, taken in 75 connection with the drawings hereto annexed, the operation and advantages of our improved engine will be readily understood by those skilled in the art to which it appertains. It is simple, powerful, durable, and economical 80 of steam. Great speed of the main shaft may be attained.

We are aware that it is old, broadly, to mount upon and drive the transporting-wheels of an engine by a rotary engine; and, further, that 85 it is old in a rotary engine to employ an eccentrically-hung disk with a sliding piston which moves in a chamber with oppositely-communicating steam-passages leading to a steam-chest having valves, &c.

Having thus described our invention, we 90 claim and desire to secure by Letters Patent of the United States—

In combination with the rotary engine having the chamber G, provided with the disk L, 95 carrying the slide N, and passages W V, and double-chambered steam-chest H, the rods and valves E' Y F'' I', lever I'', connected to shaft J, having slotted arm L', slide N', link O', lever P', lever H', the eccentric T', eccentric-strap S', 100 and connecting-link R', substantially as and for the purpose set forth.

In testimony that we claim the foregoing as our own we have hereto affixed our signatures in presence of two witnesses.

EMANUEL HAUSE.
FRANKLIN B. GRANGER.
